UNITED STATES PATENT OFFICE.

FERDINAND THIELKE, OF BROOKLYN, NEW YORK.

DESIGN FOR A HANDLE FOR BUTTON-HOOKS, &c.

SPECIFICATION forming part of Design No. 25,383, dated April 14, 1896.

Application filed February 21, 1896. Serial No. 580,266. Term of patent 3½ years.

To all whom it may concern:

Be it known that I, FERDINAND THIELKE, a citizen of the United States, residing in Brooklyn, county of Kings, State of New York, 5 have invented and produced a new and original Design for Handles for Button-Hooks and Similar Articles, of which the following is a specification, reference being had to the accompanying drawing, which shows the same 10 in side elevation applied to a button-hook.

The leading feature of my design consists of the general outline or contour of the handle, formed of compound curves, the central part or portion thereof being exaggerated, as 15 shown. The upper portion of the handle is rounded and decorated with scroll-like fig-

ures as shown at A from which the handle continues in compound curves, the central portion of the curve B being somewhat exaggerated and extending out beyond the remaining portion of the outline, the sides or surfaces of said handle being decorated with the scroll-like figures in relief, as shown at C D. 20

What I claim is—

The design, for a handle for a button-hook, 25 and similar articles, substantially as herein shown and described.

FERDINAND THIELKE.
